UNITED STATES PATENT OFFICE.

JOHN M. NASH, OF HUDSON, WISCONSIN.

MACHINE FOR PERFORATING SEAT-FRAMES.

SPECIFICATION forming part of Letters Patent No. 363,164, dated May 17, 1887.

Application filed October 25, 1886. Serial No. 217,094. (No model.)

To all whom it may concern:

Be it known that I, JOHN M. NASH, of Hudson, in the county of St. Croix, and in the State of Wisconsin, have invented certain new and useful Improvements in Machines for Perforating Seat-Frames, &c.; and I do hereby declare that the following is a full, clear, and exact description thereof.

My invention relates to machines for perforating the seat-frames or seats of chairs; and it consists in certain peculiarities of construction and combination of parts, as will be hereinafter described with reference to the accompanying drawings, and subsequently claimed.

In the drawings, Figure 1 represents a perspective view of my invention; Fig. 2, a partial front elevation showing the table-actuating mechanism in detail; Fig. 3, a horizontal section on line $x-x$, Fig. 2; Fig. 4, an under side view of the table; Fig. 5, a detail vertical section of the friction-sleeve, showing the tool-spindle in elevation; Fig. 6, an edge view of the crank-disk, and Fig. 7 a plan view of a chair-seat frame after having been operated upon by my machine.

Referring by letter to the drawings, A represents the frame of my machine, having bearings for a main shaft, B, the latter having keyed thereto a driving pulley, C, designed to be operatively connected with any suitable power. The main shaft B is also provided with a pulley, D, that is connected by means of a belt, E, with a pulley, F, on a shaft, G, the latter having its bearings in the upper part of the frame A.

The shaft G carries on its inner end a friction-disk, H, arranged to come in contact with the enlarged conical end a of a vertical sleeve, I, and a set-screw, b, is arranged to impinge against the outer end of said shaft to horizontally adjust the latter, in order to compensate for wear on the friction-disk and hold the same up to its work.

The sleeve I surrounds a spindle, J, that carries the boring-tool K, and this sleeve is provided with an internal recess or slot, c, that engages a pin, d, on the spindle, in order that both parts may revolve together and at the same time permit the necessary vertical play of said spindle.

The upper end of the spindle J is connected,

by means of a link, e, with a horizontal arm, L, that is pivotally connected to a stem, f, upwardly extended from the frame A, and a rod, g, unites the horizontal arm with a bell-crank lever, M, fulcrumed at h to said frame. 55

The bell-crank lever M has the outer end of its horizontal arm provided with a slot, i, that engages a stud, k, on a L -bolt, m, that is adjustable in a disk, N, keyed to one end of a 60 shaft, O, the latter having a bearing in the frame, A, and carrying on its end opposite the disk a pulley, P, that is connected by a belt, Q, with the main shaft B.

The vertical arm of the bell-crank lever M 65 is arranged to actuate a traveler, R, an arm, n, of which operates in a bearing, n', that forms part of or is secured to the frame A, the pivotal member R' of said traveler being provided with a spring-pawl, o, that actuates a 70 circular ratchet-plate, S, this latter part having a depending flange, p, that conforms in shape to the seat-frame or seat to be perforated. The pivotal member R' of the traveler is also provided with a pin, m', that engages an annular groove, m'', on the under side of the ratchet-plate; or, if found more desirable, a flange may be substituted for said groove and two pins be placed on said part R' to engage such flange. 75

The ratchet-plate S is provided with key-hole slots q, that engage screws r, by which said plate is detachably secured to a cross-shaped frame, T, to form what I term the "table," and the arms of said frame are provided with slots 80 s, that serve as guides for clamp-blocks U, these latter parts operating to retain the seat-frame or seat in position to be acted upon by the boring-tool K, and a pressure-foot V, pivotally connected to the frame A, is designed 85 to prevent the seat-frame or seat from binding on said boring-tool when the latter is on its return after making a perforation. 90

I may substitute a circular-plate for the cross-shaped frame T; but for some reasons the latter is to be preferred, and is therefore illustrated and more particularly described.

A hub, t, on the cross-shaped frame T, engages a pin u on an automatic sliding plate W, that operates in a corresponding groove, v, in 100 a lateral extension, A', of the frame A, and secured to this sliding plate is an arm, w, that

has pivotally secured thereto a spring pawl, w' , arranged to engage the ratchet-teeth on the plate S in opposition to the pawl o on the traveler R, thus forming a stop to prevent reverse movement of the table formed by said cross-shaped frame and ratchet-plate.

The depending flange p of the ratchet-plate S is arranged to come between two pins, p' , on the lateral extension A' of the frame A; or, if found more desirable, I may omit the flange and substitute therefor a groove that would engage a single one of said pins.

One of the arms of the cross-shaped frame is provided with a lug, y , that is arranged to come in contact with a pin, y' , upwardly projecting from the free end of an arm, y , that is pivotally secured to a rack-plate, A^2 , on the outer end and at right angles to the extension A' of the frame A.

The rack-plate serves to engage the lever-arm Z' of a tightener, Z , for the belt Q, this tightener having its bearings in a hanger, z , depending from said rack-plate and a box, z' , on the frame A. The outer end of the rack-plate is turned down and out to form a stop, z^2 , that limits the movement of the lever-arm Z' when the latter is disengaged from said rack-plate, this operation being automatically accomplished by the impingement of the lug y on the frame T against the pin y' on the free end of the arm Y .

The groove or flange p on the ratchet-plate S may be either square, round, or of irregular form, according to the pattern of the seat-frame or seat, or the design to be made by the perforations, and said plate is therefore made detachable from the clamping plate or frame T, in order that one such ratchet-plate may be substituted for another, according to the class of work to be performed.

In the operation of my invention the seat-frame or seat to be perforated is clamped on the circular table composed of the detachably-united parts S T, the lug y on the clamp-frame being just past the pin y' on the arm Y , pivoted to the rack-plate A^2 . The lever-arm Z is now engaged with the rack-plate to tighten and hold the belt Q against the main shaft B. The sleeve I is continuously revolved by the friction-disk H, and the spindle J, that carries the boring-tool K, being secured to said sleeve in the manner above described, is accordingly carried therewith. The stud l on the adjustable plate that forms part of the disk N being engaged with the slot i in the bell-crank lever M, the latter is actuated, and by its rod-connection g causes the arm L to be alternately depressed and elevated, thus vertically operating the spindle J to cause the boring-tool K to perform its function. When the tool l is boring one perforation, the pawl w' is engaged with the ratchet-plate S to hold the table (of which this plate forms a part) stationary in the desired position, while at the same time the vertical arm of the bell-crank M actuates the traveler R to carry the pawl o back to engage another ratchet-tooth, this engagement

taking place just as said boring-tool leaves the wood after having completed the perforation. As the boring-tool is carried up, the vertical arm of the bell-crank lever moves the traveler R in an opposite direction to that above described, and thus the pawl o operates to move the table one step to bring an imperforate part of the seat-frame or seat in line with said tool, and the above-described operation is continued until the lug y on the clamp-frame T comes in contact with the pin y' on the pivoted arm Y to disengage the lever-arm Z' from the rack-plate A^2 , and thus loosen the belt Q to stop the mechanism that vertically operates the spindle J and simultaneously actuates the ratchet-plate S. The circular table having made one entire revolution, the requisite number of perforations are made and such work on the seat-frame or seat, clamped to said table, completed. The seat-frame or seat is now removed from the table and another one clamped thereon and the operation above described repeated, the number of perforations in each article being equal to the number of teeth on the ratchet-plate, and the sliding-plate m in the disk N is adjusted to time the movement of the boring-tool to accord with the distance between the ratchet-teeth. When the ratchet-plate S is acted upon by the pawl o , the groove or flange p on the under side of this plate is guided by the pin or pins p' , and thus the perforations in the seat-frame or seat form a contour corresponding to that of said groove or flange, while at the same time the pin or pins m' on the pivotal member R' of the traveler are engaged by the flange or groove m^2 , also on the under side of the plate, in order to automatically bring said pawl into successive engagement with the several ratchet-teeth as the work proceeds, irrespective of the movement of the table that carries such seat-frame or seat.

I have shown the ratchet-plate in the present instance as provided with a depending flange of irregular form, it being the pattern of a seat-frame for a chair designed to be caned, and the ratchet-teeth on said plate are of such number and distance apart as to give the requisite amount of perforations necessary for the operation of caning.

The present ratchet-plate may be readily replaced by another having a different-shaped groove or flange that corresponds with some other form of seat-frame, or with some design to be made by perforations in chair-seats of the kind generally constructed by gluing and pressing together thin layers of wood, this style of chair-seat being too well known to require further description.

A machine such as I have described will be found to save a vast amount of time and labor over the methods ordinarily employed for perforating seat-frames and seats, and said machine, being mainly automatic in its action, requires but little attention, while by its use a single operative can perforate such articles in a very rapid manner without having to do more than remove each of said seat-frames or

seats from the circular rotating table when perforated, place an imperforate one in position to be acted upon, and tighten the belt that, through suitable mechanism, communicates motion to said table and the boring-tool.

Having thus fully described my invention, what I claim as new, and desire to secure by Letters Patent, is—

1. The combination of a suitable main frame, 10 a ratchet-toothed clamping-table loosely mounted thereon, a boring-tool the spindle of which has bearings in the main frame and is provided with a pin, a recessed or slotted sleeve surrounding the spindle and having one of its 15 ends provided with a conical enlargement, a friction-disk arranged to come in contact with the conical end of the spindle, a horizontal arm pivoted to the main frame and linked to said spindle, a bell-crank lever fulcrumed to 20 said main frame and connected to the horizontal arm, a traveler connected to the lever and provided with a pawl to engage the teeth on the table, a crank-disk operatively connected to said lever, and means for actuating 25 the friction-disk and crank-disk, substantially as and for the purpose set forth.

2. The combination of a suitable main frame, a table loosely mounted on the frame and having ratchet-teeth on its periphery, its under 30 side provided with an annular groove or its equivalent, and a depending flange or equivalent thereof, having any desired contour, a traveler provided with a pawl to engage the ratchet-teeth on said table, pins respectively 35 arranged on the traveler and the main frame to engage said groove and flange, a boring-tool having a reciprocating spindle that has its bearings in said frame, and a mechanism, substantially as described, for simultaneously 40 driving the boring-tool and actuating the traveler, as set forth.

3. The combination of a table, comprising a circular ratchet-plate provided upon its under side with an annular groove or its equivalent, and a depending flange or equivalent thereof, having any desired contour, and a clamping-frame detachably united to said plate, a main frame having an extension thereof provided with a sliding plate, to which the 50 table is loosely journaled, and a pin or pins that engage the depending flange or its equivalent, a stationary pawl that engages the teeth of the ratchet-plate, a traveler having an arm thereof operative in the main frame and a pivotal member provided with a pawl that also 55 engages the teeth on said ratchet-plate, and a pin or pins arranged to engage the annular groove or its equivalent in this latter plate, a boring-tool provided with a reciprocating 60 spindle operative in said main frame, and a mechanism, substantially as described, for simultaneously driving the boring-tool and intermittently actuating the traveler, as set forth.

4. The combination of a suitable main frame 65 having a lateral extension provided with a pin or pins, a sliding plate operative in said frame-

extension and carrying a pawl, a circular clamping-table loosely mounted on the sliding plate and having ratchet-teeth on its periphery to engage the pawl on said sliding plate 70 and its under side provided with an annular groove or the equivalent thereof, and a depending flange or its equivalent, of any desired contour, that engages the pin or pins on the frame-extension, a traveler having an arm 75 thereof operative in the main frame, a pivotal member carrying a pawl that engages said ratchet-teeth, and a pin or pins arranged to engage the annular groove or its equivalent in the table, a boring-tool the spindle of which 80 has bearings in the main frame and is provided with a pin, a sleeve surrounding the spindle and having one of its ends provided with a conical enlargement and a recess or slot in its body portion to engage the spindle-pin, a friction-disk arranged to come in contact with the 85 conical end of the spindle, a horizontal arm pivoted to the main frame and toggled to said spindle, a bell-crank lever fulcrumed to said main frame, connected to the horizontal arm 90 and arranged to actuate the traveler, a crank-disk operatively connected to said lever, and means for actuating the friction and crank disks, substantially as and for the purpose set forth.

5. The combination of a suitable main frame, a drive-shaft, an auxiliary shaft carrying a friction-disk, and a similar shaft carrying a crank-disk, all of said shafts being mounted in the frame and the last two independently connected with the main one by suitable belts and pulleys, a sleeve mounted in said main frame and provided at one end with a conical enlargement that comes in contact with the friction-disk, a boring-tool having its spindle fitted 100 to the sleeve to revolve therewith and have vertical play therein, a horizontal arm pivoted to the main frame and toggled to the spindle, a bell-crank lever fulcrumed to the main frame and operatively connected to the crank-disk 105 and horizontal arm, a clamping-table loosely mounted on the frame and having its periphery provided with a lug and ratchet-teeth, a pawl mechanism actuated by the bell-crank to rotate the table, and a tightener for the belt 110 that transmits motion from the main shaft to the one carrying the crank-disk, said belt-tightener having a lever-arm that engages a rack-plate on the main frame, and an arm pivotally connected to said frame and provided 115 with a projecting pin that comes in the path of the lug on the table, substantially as and for the purpose set forth.

In testimony that I claim the foregoing I have hereunto set my hand, at Milwaukee, in 125 the county of Milwaukee and State of Wisconsin, in the presence of two witnesses.

JOHN M. NASH.
